UNITED STATES PATENT OFFICE

JOHN BARRY RYAN, OF NEW YORK, N. Y.

DESIGN FOR AN AUTOMOBILE

Application filed December 9, 1931. Serial No. 42,016. Term of patent 14 years.

To all whom it may concern:

Be it known that I, JOHN BARRY RYAN, a citizen of the United States, residing at New York city, in the county of New York and State of New York, have invented a new, original, and ornamental Design for Automobile, of which the following is a specification, reference being had to the accompanying drawing, forming part thereof.

I claim:

The ornamental design for an automobile as shown.

JOHN BARRY RYAN.
